UNITED STATES PATENT OFFICE.

HORACE WYMAN, OF WORCESTER, MASSACHUSETTS, ASSIGNOR TO THE
CROMPTON & KNOWLES LOOM WORKS, OF SAME PLACE.

DESIGN FOR A DROP FOR WARP STOP-MOTIONS.

SPECIFICATION forming part of Design No. 30,899, dated May 30, 1899.

Application filed April 29, 1899. Serial No. 715,059. Term of patent 14 years.

To all whom it may concern:

Be it known that I, HORACE WYMAN, a citizen of the United States, residing at Worcester, in the county of Worcester and State of Massachusetts, have invented and produced 5 a new and original Design for a Drop for Warp Stop-Motions, of which the following is a specification, reference being had to the accompanying drawings, forming a part thereof. 10 Referring to the drawings, Figure 1 is a flat side or face view of a drop of my design, and Fig. 2 is an edge view of the same. 15 As shown in the drawings, my drop 1 is of elongated form, with straight parallel sides or edges, except at one portion of the drop near the upper end thereof, and curved ends. The drop 1 has a curved recess 2 in each edge thereof near the top portion of the drop. The recesses 2 are located opposite each other 20 to reduce the width of the drop and form a neck or reduced portion 3 intermediate the upper part and lower part of the drop.

In the upper end of the drop 1 is a circular opening or perforation 4, and just below the neck 3 is a corresponding circular opening or 25 perforation 5. In the lower half of the drop 1 is an elongated slot or opening 6.

The leading feature of my design is the recesses 2 in the opposite edges of the drop to form the reduced portion or neck 3 and the 30 openings or perforations 4 and 5 above and below said recesses and the elongated slot or opening 6 in the lower part of the drop.

What I claim is—

The design for a drop for warp stop-motions, substantially as herein shown and described. 35

HORACE WYMAN.
